CLAIM

The ornamental design for a magnetic suspension toy, as shown and described.

DESCRIPTION

FIG. 1 is a front view of the magnetic suspension toy showing my new;

FIG. 2 is a right side view thereof;

FIG. 3 is a left side view thereof;

FIG. 4 is a top view thereof;

FIG. 5 is a bottom view thereof; and,

FIG. 6 is an isometric view thereof.

The features drawn in broken lines shown in FIGS. 1-6 represent subdivisions between stacked magnets that form no part of the claimed design.
